UNITED STATES PATENT OFFICE.

HENRY JOHN DAY AND PAT JOHN WALKER, OF MOULSECOMB, ENGLAND.

DESIGN FOR A PIPE STAND.

Application filed November 14, 1922. Serial No. 4,286. Term of patent 7 years.

To all whom it may concern:

Be it known that we, HENRY JOHN DAY and PAT JOHN WALKER, subjects of the King of Great Britain, residing at Moulsecomb, in the county of Sussex, England, have invented a new, original, and ornamental Design for Pipe Stands, of which the following is a specification, reference being had to the accompanying drawing, forming part thereof.

The figure is a perspective view of a pipe stand, showing our new design.

We claim:

The ornamental design for a pipe stand as shown.

In witness whereof we affix our signatures.

HENRY JOHN DAY.
PAT JOHN WALKER.
